UNITED STATES PATENT OFFICE.

CARL F. ANDERSON, OF BROOKFIELD, ILLINOIS, ASSIGNOR TO CONLON CORPORATION,
OF CICERO, ILLINOIS, A CORPORATION OF ILLINOIS.

WASHING-MACHINE CYLINDER.

Application filed December 17, 1923. Serial No. 681,085.

To all whom it may concern:

Be it known that I, CARL F. ANDERSON, a citizen of the United States, residing at Brookfield, in the county of Cook and State 5 of Illinois, have invented a certain new and useful Improvement in Washing-Machine Cylinders, of which the following is a full, clear, concise, and exact description, reference being had to the accompanying drawings, forming a part of this specification.

The present invention relates to washing machine cylinders, and aims particularly to provide an improved construction of a metallic washing machine cylinder.

15 In the accompanying drawings, I have illustrated a preferred method of and assembly of parts for practicing my invention. In these drawings:

Fig. 1 is an end view illustrating a washing machine in phantom, and the washing machine cylinder which constitutes the present invention in full lines;

20 Fig. 2 is an elevational view of the cylinder removed from the machine, the removable cover of the cylinder being uppermost in this view;

Fig. 3 is an enlarged fragmentary sectional view taken approximately on the plane of the line 3—3 of Fig. 2;

25 Fig. 4 is a fragmentary detail section taken approximately on the plane of the line 4—4 of Fig. 6;

Fig. 5 is a similar view taken on the plane of the line 5—5 of Fig. 6;

30 Fig. 6 is a fragmentary sectional view taken transversely through the cylinder;

Fig. 7 is a detail sectional view of one of the lifters and panel interlocking strips;

Fig. 8 is a plan view of the subject matter 40 of Fig. 7, before the end of the joining has been turned under.

Fig. 9 is a view of the construction adjacent the edge of the removable cover, similar to Fig. 7; and

45 Fig. 10 illustrates a modified method of joining the inner edges of the lifters to the end heads.

Fig. 1 illustrates the present construction of cylinder in a typical installation in a reversing cylinder type of washing machine. In this type of washing machine, automatic reversing mechanism 10, which is interposed in the driving train between the electric motor 11 and the cylinder 12, functions to rotate the cylinder 12 a predetermined number

of times in one direction and to then reverse the direction of drive and rotate the cylinder an equal number of times in the opposite direction. This mode of operation will be familiar to those skilled in the art, but for specific illustration attention is directed to prior Patent No. 1,254,638 issued to Walter J. Conlon. The present improved design of cylinder may also be used in washing machines wherein the cylinder is continuously 60 rotated in one direction, or in washing machines wherein the cylinder is given an oscillatory motion of less than a complete revolution in each direction. It will be understood that the cylinder contains the clothes or other articles to be washed, and is supported in a suitable tank 13 which receives the wash water, the cylinder 12 having a multitude of perforations therein for circulating this wash water through the clothes 65 in the cylinder.

The cylinder 12 is built up of two metallic end heads 15 and a peripheral portion 16 forming the body of the cylinder between the heads. A removable cover 17, interposed in this peripheral portion 16, affords access to the interior of the cylinder. The heads are preferably bulged outwardly adjacent their centers, and the right hand end (Fig. 2) carries a mounting bracket 18 formed with a polygonal socket 19, while the left hand end carries a bracket 21 having a pintle or bearing stud 22 projecting therefrom. Each of these brackets is formed with extending spider arms which are rigidly bolted to the end heads, as shown at 23. The socket 19 is adapted to slip over a square-ended driving hub which is driven from the reversing mechanism 10, and the pintle 22 is adapted to drop into a stirrup bearing 95 secured to the other end of the tank 13.

The peripheral portion 16 of the cylinder is built up of a plurality of panels or sections 25, which are also constructed of sheet metal. I have found "half-hard" sheet aluminum as a very satisfactory metal for the construction of the end heads 15 and the panels 25. I employ No. 16 B. and S. gage for the heads and No. 20 B. and S. gage for the panels. Each panel consists of a single sheet having a series of parallel corrugations 26 extending cross wise of the cylinder. These corrugations terminate short of the lateral edges of the sheet, and the raised corrugations on the outer side of the 100

110

sheet have a plurality of perforations 27 therein for causing an inward and outward flow of the wash water through the cylinder.

It will be observed from Figures 4 and 5 that the peripheries of both end heads 15—15 are formed with an outwardly rolled semicircular flange 29. The lateral edges of the panel sheets 25 are rolled downwardly over the outer side of this flange, and up under the inner side thereof, as indicated at 31. This relation of interlocking flanges 29 and 31 securely locks the panel sheets to the end heads, and by rolling the edge of the panel sheet up under the inner side of the flange 29, there is no raw edge of the metal exposed to cutting or scratching, and consequently no finishing operation is necessary after the panels are rolled onto the end heads. The wrapping of these two flanges 20 together, in addition to forming a smooth, gradually rounded edge for the cylinder, disposes a certain amount of the stock of each end head and each panel in the most advantageous position for strengthening and reinforcing the cylinder. This permits the use of the relatively light stock employed, without the necessity of any frame or secondary reinforcing means.

The joining edges of the panel sheets 25 are interlocked by interlocking strips or connecting members 33. As shown in Fig. 6, the crosswise edge of each panel sheet 25 is turned downwardly to form the diagonal flange 34 and is then doubled back upon itself to form the locking flange 35. The lateral edges of the strips 33 are formed into converging flanges 36, which engage between the flanges 34 and 35 of adjacent panels. In assembling the panels and the interlocking strips 33, these strips are driven endwise into interlocking engagement between the pairs of flanges 34 and 35.

In the cylinders of these reversing cylinder washing machines, there are generally embodied lifters which project inwardly from the periphery of the cylinder at spaced points. These lifters raise the clothes from their immersion in the wash water and carry them up and then drop them back into the wash water, in the rotation of the cylinder. Such a lifter is illustrated by the lifters 38 shown in Figures 6, 7 and 8. In the present construction, I have utilized the lifter to reinforce the interlocked joint between adjacent panels, and conversely, I have utilized this joint to support the outer edge of the lifter. These lifters are constructed of sheet metal, preferably aluminum, having a plurality of corrugations 39 extending across the cylinder. The upper edge of the lifter sheet is rolled around a reinforcing rod 41, the rolled or beaded portion of the sheet being indicated at 42. This rolled edge 42 has a snug fit between the top of the interlocking strip 33 and the inclined sides

of the interlocking flanges 35. The ends of the lifter sheet 38 and of reinforcing rod 41 terminate substantially in contact with the inner walls of the end heads 15, as shown in Fig. 4. In assembling, the flanged edges 34—35 of the panels are assembled against the sides of the lifter 38, below the rolled edge 42, after which the flanges 36 of the interlocking strip are matched between the flanges 34 and 35, and the strip is then driven home between the flanges and over the rolled edge 42 of the lifter. The inner edge of the lifter 38 is rolled around a reinforcing rod 43, as indicated at 44. As shown in Fig. 4, the ends of this reinforcing rod 43 are threaded for the reception of screws 45 which pass through openings 46 in the end heads 15. Thus the inner edges of the lifters are held against displacement, and the screws 45 and rod 43 also function as tie connections between the end heads for additionally reinforcing the cylinder. The rod 43 may be drawn downwardly, bringing it into register with the holes 46, so as to place the lifter sheet under a slight tensile stress, and thereby hold the rolled outer edge 42 against any play in the interlocking strip 33. It will be noted that the presence of the lifter sheet 38 between the flange edges 34—35 of adjacent panels precludes any possibility of these edges moving downwardly and becoming disengaged from the interlocking flanges 36.

In Fig. 10 I have shown a modified method of connecting the inner edge of the lifter to the two end heads. In the formation of the lifter sheet the rolled inner edges 44 are made longer than the width of the sheet, so that tubular sheet metal studs 40 project laterally from the inner corners of the sheet. In assembling the cylinder, these tubular studs are inserted through holes 50 in the end heads and are then turned or flanged outwards over the outer walls of the heads, as shown at 60.

The opening into the cylinder, which is closed by the cylinder cover 17, is designated at 48, the two transverse edges of this opening being defined by lifters 38. A modified arrangement of locking strips 33' is employed in connecting the adjacent panel edges to the lifters defining this cylinder opening. One edge of each interlocking strip 33' has the usual interlocking flange 36 for engaging with the flanged edge of the panel, while the other edge is looped around the rolled edge 42 of the lifter, as indicated at 49 in Fig. 9.

As shown in Fig. 8, the flange 31 which interlocks each panel to the end head, extends along the circumferential dimension of the panel to a point close to the end of the panel. The two flanges 36—36 on the inner side of the interlocking strip are folded or pressed up closely against the

under side of the strip at the ends thereof, as indicated at 36'. These ends of the interlocking strip thus consist of two thicknesses of metal pressed together. In the 5 operation of rolling the flange 31 under the head flange 29, or, if desired, in an entirely separate operation, each double thickness end 36' on the interlocking strip is curled under the flange 29. This finishes the 10 flanged joint between the panels and end head, closing any space between the ends of the flanges 31 of adjoining panels.

The removable cover 17 comprises an aluminum casting 53 in the form of an open, 15 oblong frame, in which is mounted an aluminum panel or sheet 54, corrugated and perforated similarly to the panels 25. This frame casting is formed with an inner marginal flange 55 extending around all the 20 sides of the frame, into which the cover sheet 54 is secured, as by rivets 56 (Fig. 9). Outwardly extending marginal flanges 57 close the opening 48 at the front and rear edges of the cover. Referring to Fig. 3, it 25 will be noticed that the casting 53 is formed with lateral supporting flanges which rest on the rolled flanges 29 of the end heads 15. Guide flanges 59 also project inwardly along the sides of this cover frame or casting 30 inside of the two end heads 15.

As viewed in Figures 2 and 3, the left hand cylinder head 15 has a slot 61 cut therein substantially centrally of the cylinder opening 48. The cover is provided 35 with a hook 62 adapted to be inserted through the slot 61 in replacing the cover in the opening 48. This hook is inserted through a slot 63 in the flange 59, and has an upturned portion which is riveted to the 40 cover frame, as indicated at 64. A short section of channel 65 is secured to the outer side of the cylinder head over the outer edge of the slot 61, this section of channel having ears 66 (Fig. 1) which are 45 riveted to the cylinder head. This channel member provides a shoulder of harder metal than would the slot 61 in the aluminum head, this channel member preferably being constructed of brass or other non-rust- 50 able, relatively hard metal.

After the hook 63 is inserted through the slot 61, the other side of the cover is swung down on to the other cylinder head 15. This latter side of the cover is held down 55 by a latch 67, which has a shoulder hooking under a channel member 65 secured to this cylinder head, similarly to the channel member on the other end of the cylinder. This latch 67 is hinged upon a hinge pin 69 60 carried by a hinge bracket 71 riveted at 72 to the cylinder cover. As shown in Fig. 2, the ends of the latch pin 69 are spaced from the edges of the latch 67 to permit the coiling of a suitable spring 73 on these pin 65 ends for normally urging the latch 67 down

under the shoulder 65. The lower edge of the latch 67 is curved outwardly, as indicated at 75, so that the latch will cam itself over the flange 29 and shoulder 65 when the cover is swung down into the opening 48. 70

It will be apparent that numerous modifications and re-arrangements of parts may be made within the essence of the invention as above described.

I claim:

1. In a washing machine cylinder, the combination of a pair of sheet metal cylinder heads, a peripheral body portion between said heads comprising a plurality of sheet metal panels, the edges of adjoining panels having hook flanges thereon, sheet metal lifters in said cylinder, each of said lifters having an enlarged portion, the hook flange edges of adjoining panels being disposed in proximity to the sides of each lifter 80 inwardly of its enlarged portion, connecting strips having inwardly converged locking flanges engaging with said hook flanges and embracing the enlarged portions of said lifters, and means passing through perforations in said cylinder heads for securing the inner edges of said lifters in position.

2. In a washing machine cylinder, the combination of a pair of sheet metal cylinder heads, a peripheral body portion between 95 said heads comprising a plurality of sheet metal panels, the edges of adjoining panels having hook flanges thereon, sheet metal lifters in said cylinder engaging at their outer ends between said hook flanges, and tie bars engaging in said hook flanges to hold adjacent panels together and to clamp the outer ends of said lifters, and means for securing the inner ends of said lifters.

3. In a washing machine cylinder, the combination of a pair of cylinder heads, a peripheral body portion between said heads comprising a plurality of sheet metal panels, said panels along their adjacent edges having grooves, lifters extending at their outer ends between said panel edges, and bars having tongues for engaging in said grooves to lock the panels together and to clamp and anchor the outer ends of said lifters, and means securing the inner ends of said lifters.

4. In a washing machine cylinder, the combination of a pair sheet metal cylinder heads, a peripheral body portion between said heads comprising a plurality of sheet metal panels, said panels at their adjacent edges having grooves, lifters extending at their outer ends between said edges and having enlargements, tie bars having tongues engaging in said grooves to lock said panels together and to retain the enlarged ends of said lifters to thereby anchor them at their outer ends, and means for securing the inner ends of said lifters.

5. In a washing machine cylinder, the combination of cylinder heads, a peripheral

body portion between said heads comprising a plurality of sheet metal panels, lifters extending at their outer ends between the adjacent panels, tie means acting independently of said lifters to lock said panels together and to anchor said lifters at their outer ends, and means securing the inner ends of said lifters.

6. In a washing machine cylinder, the combination of a pair of sheet metal cylinder heads, a peripheral body portion between said heads comprising a plurality of sheet metal panels, said panels having grooves along their edges, tie bars extending across said body portion and extending a distance beyond said heads, said bars having tongues engaging in said grooves to thereby lock said panels together, the adjoining edges of said heads and panels, together with the projecting ends of said bars, being seamed together.

7. In a washing machine cylinder, the combination of cylinder heads, a peripheral body portion between said heads comprising a plurality of sheet metal panels, said

panels at their adjoining edges having grooves, lifters having enlargements at their outer ends and engaging between the panel edges, and tie bars bridging said enlarged ends and having locking flanges engaging in said grooves whereby said panels are locked together, and means securing the inner ends of said lifters.

8. In a washing machine cylinder, the combination of cylinder heads, a peripheral sheet metal body portion extending between said heads having an opening, the edges of said body portion at said opening being deflected to form grooves, a radial wall extending from each of said edges and having an abutment, and a tie bar at each of said edges having a locking flange engaging in the respective grooves and having another locking flange receiving the abutment of the respective radial wall to thereby secure said wall to said body portion, and means securing the inner ends of said radial wall.

In witness whereof, I hereunto subscribe my name this 30th day of November, 1923.

CARL F. ANDERSON.
